*By Joulman and Joulman,
ATTORNEYS.*

UNITED STATES PATENT OFFICE.

THOMAS EASTHAM HANSFORD, OF BRISTOL, ENGLAND.

TOBACCO PIPE.

Application filed June 3, 1926, Serial No. 113,388, and in Great Britain June 4, 1925.

This invention relates to tobacco pipes of the type comprising a bowl, a detachable mouthpiece, and an inner tube mounted in said mouthpiece and adapted to project through the pipe stem into the bottom of the bowl, the tube being of such a diameter as to fit the normal smoke passage of the pipe.

The object of my invention is to provide an improved tobacco pipe of this type which will be hygienic and easily cleanable and comprises the combination of a device hereinafter described and defined in the appended claim.

A further object of the invention is to provide a pipe of this character comprising a minimum number of parts and requiring no screw threaded portions.

The invention will be made more clear by referring to the accompanying drawings in which:—

Fig. 1 shows one form of pipe made in accordance with this invention in section; and

Fig. 2 shows the component parts thereof.

The improved pipe shown is built up of a bowl *a*, a stem *b*, and a detachable mouthpiece *c*. The joining ends of the stem and mouthpiece are so fashioned that the mouthpiece will extend into the stem a sufficient distance to unite them, the end *f* of the stem abutting against the shoulder *g* on the mouthpiece. A glass tube *d*, which is straight throughout its length and of symmetrical cross section, is inserted in the stem and is held in position in the ends of the mouthpiece by means of a tapered ferrule *e* of any suitable elastic material, cork having been found to give satisfactory results. The interior of the connecting end of the mouth-

piece is so fashioned that there will be a tight fit between the ferrule and the mouthpiece, whereby the glass tube is sustained in proper relation to convey the smoke from the bowl to the mouth. The end of the inner tube projects through the stem *b* into the bottom of the bowl *a*.

In use, as soon as the tobacco is burned, the smoke passes into the glass tube without coming into contact with any wooden or other portion of the pipe except the bowl, and thence issues into the mouthpiece. Further, there are no kinks or bends or hollows in the pipe which would be liable to collect any nicotine or other extraneous matter.

It will thus be seen that a pipe made in accordance with my invention requires only a minimum number of parts and has no screw threaded portions to become worn, in addition to the advantage of conveying the smoke directly from the bowl through a glass tube to the smoke channel in the mouthpiece.

What I claim and desire to secure by Letters Patent is:—

A four piece tobacco pipe comprising a bowl, a recessed stem in one with the bowl, a mouthpiece adapted to fit within the recessed stem, a recess in the mouthpiece, a single glass tube extending from the bowl to the recess in the mouthpiece, a tapered cork surrounding the glass tube at one end and adapted to connect the glass tube to the mouthpiece, the enlarged end of said tapered cork lying in the recess of the stem, whereby no nicotine or other extraneous matter can be collected in the smoke passage.

In testimony whereof, I affix my signature.

THOMAS EASTHAM HANSFORD.
